UNITED STATES PATENT OFFICE.

JAMES BARKER, OF KALAMAZOO, MICHIGAN.

TEMPORARY BINDER.

1,384,883.

Specification of Letters Patent. Patented July 19, 1921.

Application filed October 29, 1920. Serial No. 420,368.

To all whom it may concern:

Be it known that I, JAMES BARKER, a citizen of the United States, residing at the city and county of Kalamazoo, State of Michigan, have invented certain new and useful Improvements in Temporary Binders, of which the following is a specification.

This invention relates to improvements in temporary binders.

10 My improved temporary binder relates particularly to the type of binder which has become known to the trade as "tray binders," such binders being used particularly for machine accounting where it is desired 15 to remove the sheets from the binder for making the records, the binder members being separated to facilitate the removing and replacing of the sheets.

It is the main object of this invention to 20 provide an improved temporary binder provided with a removable locking post for the sheets in which the binder members cannot be secured together without the placing of the sheet locking post thereby insuring the 25 securing of the sheets.

A further object is to provide a structure having these advantages which is comparatively simple, economical to produce and easy to manipulate.

30 Further objects, and objects relating to structural details, will definitely appear from the detailed description to follow.

I accomplish the objects of my invention by the devices and means described in the 35 following specification. The invention is clearly defined and pointed out in the claims.

A structure which is the preferred embodiment of my invention is clearly illustrated in the accompanying drawing forming 40 a part of this specification, in which:

Figure I is a rear perspective view of a binder embodying the features of my invention.

Fig. II is a longitudinal section through 45 the binder members on a line corresponding to line 2—2 of Figs. III, IV and V, parts being shown in full lines for convenience in illustration.

Fig. III is a detail section on a line corresponding to line 3—3 of Fig. V.

Fig. IV is a detail section on a line corresponding to line 4—4 of Figs. II and V.

Fig. V is a detail section on a line cor-

responding to line 5—5 of Figs. II, III and IV.

Fig. VI is a plan view of the locking bar or slide.

Fig. VII is a perspective view of one of the post socket members.

Fig. VIII is a detail section corresponding to that of Fig. II showing a modified arrangement of locking post.

Fig. IX is a detail plan view of a sheet adapted for the binder illustrated.

Fig. X is a detail view showing the binder members separated.

Fig. XI is a longitudinal section through the binding members on a line corresponding to line 11—11 of Fig. XII showing another modification in which the movable post constitutes a locking member for the binder.

Fig. XII is a detail plan view of structure shown in Fig. XI.

In the drawing similar reference characters refer to similar parts throughout the several views, and the sectional views are taken looking in the direction of the little arrows at the ends of the section lines.

Referring to the drawing, 1 and 2 designate the binder members generally, and 3 the covers which are secured to the binder members by the hinges 4. The binder members are provided with telescoping back flanges 5. The binder member 2 is chambered to house the mechanism of the binder. The binder member 1 is provided with relatively fixed posts 6 while the binder member 2 is provided with relatively fixed posts 7. These posts as illustrated are of the sectional type.

Each binder member is provided with openings adapted to receive the posts carried by the other binder member.

The locking bar or slide 8 is supported by plates 9 and screws 10, the screws being carried by the inner wall of the binder member 2 and arranged through slots 11 in the locking bar to engage the plates 9 as clearly shown in Fig. II. The locking bar is provided with a finger piece 12 projecting through a hole 13 in the inner wall 14 of the binding member 2.

The coiled spring 15 is connected to the locking bar to urge it to locking position.

I also provide a removable sheet locking

post 16, the sheet 17 (see Fig. IX) being provided with notches 18 to receive the relatively fixed posts, and a hole 19 to receive the removable locking post 16 so that when sheets are assembled in the binder with the post 16 engaging the holes 19 the sheets are securely retained, but upon removal of the post 16 they are all freed.

The binder member 2 is provided with 10 socket members 20 for the ends of the posts 6 and removable post 16. These socket members 20 are provided with vertical slots 21 and are cut away at 22 at their upper ends to permit the reduced portions 23 of the key-hole slots 24 to pass into the sockets so that the locking bar engages the groove-like recess 6' of the posts 6 thereby locking the parts together. The enlarged portions of the openings 24 are of such size as to permit 20 the insertion and removal of the posts when these enlarged portions are in alignment with the sockets. A similar keyhole slot or opening 24' is provided for the removable post 16. However, in this embodiment of 25 my invention the locking bar does not perform any locking function for the removable post.

In the socket 20' for the removable post 16 I arrange a disk-like detent 25 which is engaged by the spring 26 disposed through the detent and through the openings 21 in the socket, the ends of the spring engaging the wall of the binder member urging the detent normally upward, and when the locking bar is in its disengaged position the detent member passes into opening 24' thereof, thereby preventing the locking movement of the locking bar until the detent is disengaged, and this is automatically done by the closing of the binder members with the locking post in position. If an attempt be made to close the binder without the locking post in position, the locking bar cannot be actuated to engage the posts 6, and the operator is thereby made aware of the fact that he has omitted the locking post. The advantage of this is that operators in closing binders of this type frequently neglect to introduce the locking post when binder is closed, and when they are picked up the sheets fall out.

Disks 25' are provided for the sockets 20. While these disks of the sockets 20 do serve as means for locking the locking bar that is not their main function, as the detent 25 answers the purpose. These disks 25' are provided as a means of ejecting the posts 6 from the sockets when the locking bar is disengaged.

In Fig. VIII I show an adaptation in which locking post 27 is introduced from the outside of the binder member 1', said binder member having a recess 28 therein adapted to receive the head 29 of the post 27, there being a slot 30 in the bottom of the

recess permitting the passage of the retaining pin 31 so that the pin may be introduced through the slot and the post turned to engage the pin with the binder member. In this embodiment, however, the post can be 70 removed after the binder is locked and thereby free the sheets.

In the embodiment shown in Figs. XI and XII binder members 32 and 33 are similar in structure to that of the second embodiment, none of the fixed posts 34, however, performing any locking function.

The locking bar 35 is provided with a locking slot 36 adapted to coact with the recess 37 of the removable post 38. This post 38 is removable through the binder member 32 which is provided with a recess 39 for the head of the post. The locking bar 31 is provided with an actuating spring 40 while the removable post has a socket 20' and detent 25 substantially the same as in the preferred embodiment.

In the construction in Figs. XI and XII it is possible to release the sheets by removing the post 38 while the binder is still 90 closed. It is, however, impossible to lock the binder until the post 38 has been inserted.

My improved temporary binder is comparatively simple, is quite economical in structure and very convenient to use.

I have illustrated an adaptation or embodiment of my invention which I find very satisfactory. I have not attempted to illustrate certain modifications and adaptations 100 of my improvements to other binders which I contemplate, as I believe the disclosure made will enable those skilled in the art to which my invention relates to embody or adapt same as may be desired.

Having thus described my invention, what I claim as new and desire to secure by Letters Patent is:

1. In a temporary binder, the combination of binder members, a removable post, a relatively fixed post mounted on one of said binder members, a locking bar provided with keyhole openings slidably mounted in the other binder member, socket members for said fixed and removable posts in said other binder member, said socket members being vertically slotted and being disposed so that the enlarged portion of the keyhole slots register with the socket openings thereof when the locking bar is in its disengaged position and the smaller portions of the slots pass into the socket members engaging the fixed post when the locking bar is in locking position, an actuating spring for said locking bar, disk-like detents arranged in said sockets, and actuating springs for said detents arranged through the vertical slots in said socket members whereby the detents are urged upwardly to engage said locking bar and hold it in inoperative position 130

- when the posts are removed from the sockets, said detent springs also acting to eject the posts when said locking bar is disengaged therefrom.
5. 2. In a temporary binder, the combination of binder members, a removable post, a relatively fixed post mounted on one of said binder members, a locking bar for said fixed post provided with keyhole openings slidably mounted in the other binder member, socket members for said fixed and removable posts in said other binder member, detents arranged in said sockets, and actuating springs for said detents whereby the detents are urged upwardly to engage said locking bar and hold it in inoperative position when the posts are removed from the sockets, said spring also acting to eject the posts when said locking bar is disengaged therefrom.
10. 3. In a temporary binder, the combination of binder members, a removable post, a relatively fixed post mounted on one of said binder members, a locking bar for said fixed post slidably mounted in the other binder member and having a keyhole slot therein, a socket member for said removable post, said socket member being vertically slotted and being disposed so that the enlarged portion of the keyhole slot registers with the socket opening when the locking bar is in its disengaged position and the smaller portion of the slot passes into the socket member when the locking bar is in locking position, an actuating spring for said locking bar, a disk-like detent arranged in said socket, and an actuating spring for said detent arranged through the vertical slots in said socket member whereby the detent is engaged with said locking bar and holds it in inoperative position when the removable post is removed from its socket.
15. 4. In a temporary binder, the combination of binder members, a removable post, a relatively fixed post mounted on one of said binder members, a locking bar for said fixed post slidably mounted in the other binder member, a socket member for said removable post provided with vertical slots, a detent arranged in said socket, and an actuating spring for said detent arranged through the vertical slots in said socket member whereby the detent is engaged with said locking bar and holds it in inoperative position when the removable post is removed from its socket.
20. 5. In a temporary binder, the combination of binder members, a relatively fixed post carried by one of said binder members, a post locking bar disposed in the other binder member and provided with a keyhole slot adapted to receive said fixed post, said fixed post being notched to receive the reduced portion of said slot, a spring urging said locking bar to locking position, a removable post, and a detent for holding said locking bar in inoperative position adapted to be disengaged by said removable post, all co-acting for the purpose specified.
25. 6. In a temporary binder, the combination of binder members, a relatively fixed post carried by one of said binder members, a post locking bar disposed in the other binder member, a spring urging said locking bar to locking position, a removable post, and a detent for holding said locking bar in inoperative position adapted to be disengaged by said removable post, all co-acting for the purpose specified.
30. 7. In a temporary binder, the combination of binder members provided with telescoping back members, a fixed post mounted on one of said binder members, a locking member mounted on the other binder member to coact with said fixed post, means for holding said locking member in inoperative position, and a removable post constituting means for releasing said holding means.
35. 8. In a temporary binder, the combination of binder members, a fixed post mounted on one of said binder members, a locking member mounted on the other binder member to coact with said fixed post, means for holding said locking member in inoperative position, and a removable post constituting means for releasing said holding means.
40. 9. In a temporary binder, the combination of binder members, a relatively fixed post carried by one binder member, a locking member carried by the other binder member to coact with said relatively fixed post, a spring actuating means for said locking member, a detent for holding said locking member in inoperative position, and a removable post constituting means for releasing said detent.
45. 10. In a temporary binder, the combination of binder members, relatively fixed posts carried thereby, a locking member carried by one of said binder members, a spring actuating means for said locking member, a detent for holding said locking member in inoperative position, and a removable post constituting means for releasing said detent.
50. 11. In a temporary binder, the combination of binder members, relatively fixed posts carried thereby, a locking member carried by one of said binder members, a detent for holding said locking member in inoperative position, and a removable post constituting means for releasing said detent.
55. 12. In a temporary binder, the combination of separable binder members, a spring actuated means for locking said binder members, a detent for holding said locking means in inoperative position, and a removable post constituting means for releasing said detent as specified.
60. 13. In a temporary binder, the combina-

tion of binder members, a locking means therefor, and a removable post constituting a control for said locking means whereby the locking means is operative to lock the binder only when the removable post is in position.

In witness whereof, I have hereunto set my

hand and seal in the presence of two witnesses.

JAMES BARKER. [L.S.]
